UNITED STATES PATENT OFFICE.

HENRY C. SWAN, OF CLEVELAND, OHIO.

COMBINED DASH-FOOT AND DASH-BRACE.

SPECIFICATION forming part of Letters Patent No. 758,393, dated April 26, 1904.

Application filed January 2, 1904. Serial No. 187,406. (No model.)

To all whom it may concern:

Be it known that I, HENRY C. SWAN, of Cleveland, Cuyahoga county, Ohio, have invented a new and useful Combined Dash-Foot and 5 Dash-Brace for Vehicles, of which the following is a full, clear, and exact description, reference being had to the accompanying drawings, forming part of this specification, in which—

10 Figure 1 is a side elevation, partly in section, showing my combined dash-foot and dash-brace; and Fig. 2 is a plan view thereof.

My invention provides a combined dash-foot and dash-brace for vehicles in which the dash-foot proper is made separate from the dash-brace attachment or brace and is adapted to interlock with the latter in such manner that the dash-brace attachment can be applied to the dash-foot after the dash-foot has been secured to the vehicle-body. This enables the user of the device to put the parts together as they are required in the different processes of manufacturing the vehicle, the dash-foot being applied to the body in the earlier stages of 20

25 the manufacture, so as to make it convenient to handle the body while it is being passed through the shop in the various processes of manufacture, and the dash-brace attachment being applied later when the dash is assembled 30 with the body. This facilitates and reduces the cost of the manufacture of the vehicle and could not be done if the dash-brace attachment or brace were made integral with the dash-foot or were adapted to be connected therewith in 35 such a manner as to require their assembling before the dash is applied to the vehicle.

In the accompanying drawings, 2 represents the dash-foot, having a portion *b*, which is adapted to be bolted or otherwise secured to 40 the vehicle-body, and having, preferably, an upwardly-extending portion *c*, which is adapted to be secured to the dash. The toe-rail attachment or dash-brace 3 extends upwardly at an angle from the dash-foot and is adapted to

be secured to the toe-rail at *d* and to the dash 45 at *e*. At its lower end it is provided with a hook *f*, which is adapted to take into a hole *g*, formed in the dash-foot, and is preferably provided with a shoulder *h*, so that when inserted into the hole it will rest on the dash-foot and will be supported thereby in an upwardly-inclined position. This device enables the brace to be inserted into the dash-foot from above after the dash-foot has been applied to the vehicle-body and makes the parts readily 50 detachable.

Within the scope of my invention as broadly considered other means of attachment of the brace to the dash-foot after the dash-foot has been set on the vehicle-body may be substituted.

I claim—

1. A combined dash-foot and dash-brace comprising a dash-foot portion adapted to be secured to the vehicle-body, and a separate 65 dash-brace portion having interlocking engagement with the dash-foot; substantially as described.

2. A combined dash-foot and dash-brace comprising a dash-foot portion adapted to be 70 secured to the vehicle-body and having a recess and a separate dash-brace having a hook adapted to take into said recess; substantially as described.

3. A combined dash-foot and dash-brace 75 comprising a dash-foot portion having a recess, and adapted to be secured to the vehicle-body, and a separate dash-brace having a hook adapted to take into the recess in the dash-foot and provided with a shoulder to engage 80 the dash-foot; substantially as described.

In testimony whereof I have hereunto set my hand.

HENRY C. SWAN.
